UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

NEEDLE-SHOGGING MECHANISM

Application filed April 2, 1927. Serial No. 180,527.

This invention relates to new and useful improvements in needle shogging mechanisms for blind stitch sewing machines, and has for its principal object to provide a shogging mechanism wherein the needle lever is positively moved during both strokes of each reciprocation whereby the needle will enter the fabric with certainty at the predetermined points of needle penetration.

With these and other objects in view which will more fully appear, the nature of the invention will be more clearly understood by following the description, the appended claim, and the several views illustrated in the accompanying drawings.

In the accompanying drawings which show one form of my invention:

Figure 1 is a front elevation of a stitching head, of a Lewis type of blind stitch sewing machine, showing the application of my invention,

Figure 2 is a rear elevation thereof,

Figure 3 is a perspective view showing the needle lever and the driving mechanism therefor,

Figure 4 is a detailed sectional view showing the sliding connection between the needle lever hub and the actuating bell crank lever,

Figure 5 is a detailed view showing the needle lever hub, the peripheral slot therein, and the sliding block which is carried by the actuating bell crank lever, and

Figure 6 is an enlarged plan view showing the peripheral cam for imparting the shogging movements to the needle lever.

Like numerals designate corresponding parts throughout the several figures of the drawings.

Referring to the accompanying drawings, I have shown my invention as applied to the stitching head 5 of a Lewis type of blind stitch sewing machine.

The needle 6 is fixed to one arm 7 of a needle lever 8 having a hub 9 journaled on a horizontal shaft 10 fixed to the stitching head 5. The needle 6 cooperates with a supplemental stitch forming mechanism which in this instance is indicated as a rotary hook 11 arranged directly in front of the needle 6.

The horizontal shaft 10 has its axis in a plane

at right angles to the line of feed and consequently in the construction shown the needle 6 will oscillate in plane parallel to the line of feed.

In order to oscillate the needle lever 8 about its supporting shaft 10, I have connected the other arm 12 of said needle lever with a vertically disposed link 13, the upper end of the link being pivotally connected to one arm 14 of a bell crank lever 15 which is fulcrumed on the stitching head 5 as at 16. The other arm 17 of the bell crank lever is pivotally connected to the lower end of a pitman 18 and the upper end of this pitman is pivotally connected to an eccentric pin 19 fixed to the end of a horizontal jack shaft 20 which is journaled in the stitching head 5. This shaft is rotated from the main shaft 21, which is also journaled in the head 5, through the medium of a "1 to 1" gear coupling 22.

In order to permit the needle lever 8 to reciprocate along its supporting shaft 10 so as to impart shogging movements to the needle, I have provided the lower end of the link 13 with a fixed pin 23 and the arm 12 of the needle lever 8 not only has pivotal connection with said pin but is also capable of having sliding movements relative thereto. Thus when the needle lever 8 is bodily reciprocated along the shaft 10, the arm 12 of said lever will also move bodily longitudinally of the pin 23.

In order to provide a mechanism for effecting positive shogging movements to the needle lever 8 during each reciprocation thereof, I have provided the hub 9 of said needle lever with a peripheral groove 24 resulting from spaced flanges 25—25 formed on the hub 9. A bell crank lever 26 is fulcrumed at its angle, as at 27, to the stitching head 5 at a point directly above the groove 24, and this bell crank lever includes a vertical arm 28 and a horizontal arm 29. The vertical arm 28 extends downwardly to a point in front of the flanges 25, and secured to the lower end of the arm 28 is a block 30 which has sliding connection within the groove 24 and against the inner faces of the flanges 25. The horizontal arm 29 of the bell crank lever is provided with a

cam fork 31 which has direct contact at all times with the periphery of an actuating cam 32. This cam 32 is provided with two concentric peripheral portions 33 and 34, respectively, of different radii, the portion 33 having the largest radius. These concentric portions are disposed opposite to each other, and the portion 33 extends from the point *a* to the point *b*, as shown in Fig. 6, whereas the portion 34 extends from the point *c* to the point *d*. The axis of the cam is indicated at 35. The cam 32 is fixed to a horizontal shaft 36 which is driven from the hook shaft 37 by means of a "1 to 4" gear coupling 38. The hook shaft 37 is journaled at the rear of the stitching head 5 and is operatively connected to the hook 11. The upper end of the hook shaft 37 is driven from the gear coupling 22 by a "1 to 2" gear 39, whereby the hook shaft 20 will be rotated twice to every revolution of the main shaft. Consequently, the needle lever 8 will be oscillated during every rotation of the main shaft 21, whereas the cam 32 will be given a complete rotation during every two 25 complete oscillations of the needle lever.

As the result of the above construction, the cam 32 will impart positive shogging movements to the needle lever during each full reciprocation of the needle lever along its shaft 30 10, thereby insuring the point of the needle entering the material at predetermined points.

It is of course to be understood that the details of structure and arrangements of parts 35 may be variously changed and modified without departing from the spirit and scope of my invention.

I claim:

A needle shogging mechanism for blind 40 stitch sewing machines comprising in combination, a stitching head, a horizontal shaft fixed to said head, a needle lever having a hub fulcrumed on said shaft, means for oscillating said needle lever, said hub having a peripheral groove, and means for reciprocating said needle lever along said shaft comprising a bell crank lever fulcrumed on said head above said groove and including a vertical arm and a horizontal arm, means carried by 45 the vertical arm for sliding engagement with the peripheral groove of the hub, a cam block fixed to the horizontal arm, a peripheral cam cooperating with said cam block for imparting positive strokes to the needle lever during 50 each complete reciprocation thereof, said cam including oppositely disposed concentric peripheral portions of different radii, and means for rotating said cam once during 55 every two complete oscillations of the needle lever.

In testimony whereof I hereunto affix my signature.

CHARLES W. MUELLER.
